UNITED STATES PATENT OFFICE.

HARRY F. LOWE AND PAUL BROCKETT, OF WASHINGTON, DISTRICT OF COLUMBIA.

PAPER RECEPTACLE.

1,233,802.

Specification of Letters Patent.

Patented July 17, 1917.

Application filed July 10, 1915. Serial No. 39,105.

To all whom it may concern:

Be it known that we, HARRY F. LOWE and PAUL BROCKETT, citizens of the United States, residing at Washington, in the District of Columbia, have invented new and useful Improvements in Paper Receptacles, of which the following is a specification.

This invention relates to certain new and useful improvements in paper receptacles and pertains more particularly to receptacles used as a container for lubricants, pastes and like substances.

The primary object of the invention is to provide a container for the aforementioned purposes which is made of paper so as to avoid or eliminate metal in the body construction, since metal, especially tin, is becoming scarce and its cost is accordingly increasing.

A further object of the invention is to provide improved means for effecting connection of the neck or spout of the container with the paper body, which means allows the connection to be effected mechanically without the use of adhesives, tacks, or the like.

A still further object of the invention is to provide a paper receptacle the body of which is reinforced so as to assure same withstanding rupture or breakage in use, and to provide a receptacle which is of economical construction and which possesses minimum of parts.

Further and other objects of the invention will be later herein set forth and evidenced in the course of the following description.

In the drawings:

Figure 1 is a side elevation of the invention;

Fig. 2 is a section on the line 2—2 of Fig. 1;

Fig. 3 is a section on the line 3—3 of Fig. 1;

Fig. 4 is a plan view, partly broken away, of the key;

Fig. 5 is a side elevation of the securing ring; and

Fig. 6 is a like view of the neck.

In proceeding in accordance with the present invention, the body is formed of paper reinforced by a sheet of gauze, the process of formation being preferably, though not necessarily as follows: A continuous sheet of paper 1 is wound about a mandrel until the sheet overlaps on edge

of 2 as indicated at 3, whereupon a sheet of gauze 4 is inserted and placed on top of the wound paper and wound thereabout to form a second layer and is of a width to 60 terminate in proximity but beyond the point 3 aforementioned, whereupon the remainder of the continuous endless paper sheet 1 is then wound about and over the gauze sheet and beyond the point 3. In this process the materials used in the construction of the walls are bound together with any suitable waterproofing adhesive, such as one containing paraffin, which permeates the walls, filling the pores of the paper and 70 gauze, making them impervious to fatty and resinous substances, liquids and substances which easily liquefy.

The whole then constitutes a tube of any shape, the walls of which are made up of 75 two layers of paper reinforced and strengthened by a layer of gauze in and between.

The body after formation is in tubular form, and is then ready to receive the neck portion which latter consists of a neck 80 proper 7 formed of wood or paper composition, or other suitable material, having a circularly flanged base 8. The flanged base 8 is inserted in an end of the tubular body and the latter is then gathered in the form of a 85 reinforced collar to cover and snugly embrace the periphery of the base 8, following which a metal disk 9 having a central aperture to receive the neck is placed over the latter, the disk 9 having a depending flange 90 or skirt 10, of a diameter to engage above and around the free edge portions of the body that are gathered about the periphery of the flanged base 8. The disk 9 is moved down so as to seat on top of the end of body 95 1 which latter is bent to extend inwardly over the flanged base 8, and by means of a prick punch or the like, teats 11 are struck inwardly of and out from the skirt 10 so as to be embedded in or projected into the base 100 of the neck, whereby the paper body is more effectively united to the neck without the use of fastening means extraneous to the metal disk. Any type of closure 12 may be used to close the neck, which closure may be threaded onto the neck, as depicted in the drawings, or may be otherwise appropriately held thereto, so as to enable removal and replacement as desired.

It is particularly to be noted that the neck 110 may be made of any desired length so as to serve as a spout to allow the easy and expe-

ditious introduction of lubricant, *i. e.* in cases where the device is used to feed lubricant, to the transmission or other parts of an automobile.

- 5 The device as above described and assembled is now ready for filling, the substance being introduced through the open lower or opposite end of the receptacle, and upon completion of the filling operation, the last 10 named end of the body is then flattened in a straight line, and doubled over onto the flattened shank 13 of a suitable key 14, following which a strip of metal of U-shape in cross section is placed over the doubled over 15 edge of the body end, and secured by the formation of teats 15 in a manner similar to the formation of the teats 10 as hereinabove described.

What is claimed is:

- 20 1. In a paper receptacle, a body, a neck having a circularly flanged base, the body having an open end which is gathered about the periphery of the flanged base, and a disk having an opening which receives the neck 25 and which seats on top of the base, said disk having an integral depending skirt which engages above and around the gathered parts of the body, and said skirt having teats forced outwardly therefrom and projected 30 through the body gatherings into the base of the neck.
2. In a paper receptacle, a body open at one end, a flanged neck inserted in said body end, said body end being of tubular form to 35 engage over the flange periphery and being inturned over the outer face of the flange, and means seating on the inturned end of the body to hold the same on the outer face of the flange and embracing the part of the

body that engages the periphery of said neck 40 flange to hold the body end on the neck.

3. In a paper receptacle, a body open at one end, a neck having a flange about the periphery of which the open end of the body is contracted, and a disk apertured to receive 45 the neck and provided with a depending flange encircling the contracted body portion to retain the same in close embrace with the periphery of the neck flange.

4. In a paper receptacle, a body open at 50 one end, a neck having a flange about which the body engages and over which said body is bent to engage the upper face of the flange, and a disk apertured to receive the neck and seat on the inturned end of the 55 body to hold the same on the upper face of the neck flange, said disk having a skirt surrounding the adjacent part of the body to hold it in close embrace with the neck flange.

5. In a paper receptacle, an open ended 60 body having an axially extending collar, a neck which the collar closely embraces, and an apertured disk receiving the neck and extending over the edge of the collar, said disk having a part depending about the periphery of the collar and said depending part having means for securing the collar to the neck, said securing means extending radially through the collar.

In testimony whereof we have hereunto 70 set our hands in presence of two subscribing witnesses.

HARRY F. LOWE.
PAUL BROCKETT.
